DRUMMER'S STOOL

Bob C. Rente, Alamosa, Colo.

Application December 10, 1943, Serial No. 513,763

4 Claims. (Cl. 206—13)

This invention relates to a drummer's stool, and has for the primary object the provision of a device of this character which besides providing a comfortable seat for a person while playing a bass drum and other accompanying musical instruments, also will provide a case in which the drum beating means, the cymbal actuating means along with other musical equipment may be placed to permit transportation thereof from place to place conveniently and which will provide full protection thereto while not in use or when in storage, requiring only a limited space for its accommodation.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a top plan view, partly in section, illustrating a drummer's stool constructed in accordance with my invention and showing a drum supported thereby and also the crash cymbals usually played with the bass drum and accessories which may be used in connection therewith.

Figure 2 is a vertical sectional view showing the mechanism for beating the drum and for the support thereof in operative or playing position and further showing how the device may be folded and arranged within the case of the stool, and taken on line 2—2 of Figure 1.

Figure 3 is a sectional view taken on the line 3—3 of Figure 2.

Figure 4 is a vertical sectional view showing the crash cymbals, its support and operating means connected with the stool.

Figure 5 is a fragmentary vertical sectional view showing the door of the case in an open position and further illustrating the operating means of the crash cymbals folded and arranged within the case.

Figure 6 is a sectional view taken on the line 6—6 of Figure 4.

Figure 7 is a detail sectional view taken on the line 7—7 of Figure 4.

Figure 8 is a fragmentary front elevation showing the interior of the door equipped for supporting playing equipment and tools which may be used in the adjustment of the musical instrument as well as the equipment forming part of the present invention.

Figure 9 is a fragmentary vertical sectional

view illustrating a joint in the stand of the crash cymbals to permit such stand to be folded.

Figure 10 is a fragmentary side elevation showing a portion of the stand in a folded position.

Referring in detail to the drawings, the numeral 5 indicates a case, preferably of a size and shape that it can be conveniently carried from place to place and is provided with a handle 6 to facilitate the carrying thereof. The front of the case is fully open and is normally closed by a hinged door 7 held closed by a suitable latch 8.

Arranged vertically in the case is a tubular post 9, the lower end of which may be suitably fastened on the bottom wall of the case while the upper end is extended through the top wall of the case in order that a threaded stem 10 of a stool seat 11 may be threaded in the post for arrangement over the case to be utilized by a person while playing a drum and other instruments which usually accompany the playing of the drum. The post 9 is internally threaded to receive the stem 10 so that the stem can be removed from the post and the seat arranged within holders 12 provided in the case when the seat is not in use. The holders 12 may be of any desired construction and preferably arranged so that the seat can be easily applied and removed when desired. The stem being threaded in the post will permit the seat to be raised and lowered to suit the desires of the player.

The post has connected thereto a foldable drum supporting means 13 and a cymbal actuating means 14 also of a foldable character. Said means 13 and 14 being foldable may be readily arranged within the case or extended therefrom, as shown in Figure 1, so that the feet of the player sitting upon the seat can be placed upon treads carried by said means for the actuation of the drum as well as the cymbals.

The drum supporting means 13 is pivotally mounted on a collar 15 fixed to the lower portion of the post so that said drum supporting means may be brought into the case and swung outwardly thereof when desired. In order that the drum supporting means can be accommodated in the case and only require a comparatively small space therein it is composed of sections 16, 17 and 18 hinged together whereby the section 18 may be swung to engage with the section 17 as indicated in dotted lines in Figure 2, and the section 17 then swung upwardly along with the section 16 to assume a folded position within the case, as shown in Figure 2. A strap including a buckle is employed for holding the drum supporting means folded within the case

and is indicated by the character 19 being suitably secured to the post 8. The section 16 is composed of telescopic sections whereby said section 16 may be adjusted as to length for varying the distance of the drum from the case when in playing position. A bolt and nut, indicated by the character 20, secures the telescopic sections against movement.

When the drum supporting means 13 is arranged outwardly of the case in playing position, the sections 17 and 18 rest flatly on the floor and the section 18 is equipped with a fixed jaw 21 and also with a movable jaw 22. The movable jaw is suitably mounted for sliding movement on the section 18 and may be adjusted toward and from the fixed jaw 21 through the operation of a feed stem 23 threaded to the movable jaw and journaled on the section 18. The jaws will permit different size drums to be secured on the section 18 and easily detached therefrom.

A support 24 is secured on the section 17 adjacent the section 18 for the pivotal support of a drum beating element or mallet 25. The support 24 may be folded down on the section 17 when it is desired to fold and arrange the drum supporting means within the case.

One of the foot treadles heretofore referred to and indicated by the character 26 is hinged on the section 17 and is connected to the beating element 25 by a link 27 so that the person occupying the stool seat may, through the use of one foot on the treadle 26, actuate or beat the drum. The link 27 is preferably detachably connected to the foot treadle 26 so that it may be disconnected therefrom when the drum supporting means is being arranged for folding.

By referring to Figure 1 it will be seen that the drum supporting means when in operative position extends outwardly of the case by way of the doorway extending at an angle to the post, while the cymbal operating means extends in diverging relation thereto from the post through the doorway. The collar 28 to which the cymbal supporting means 14 is pivoted is journaled on the post which will permit said supporting means 14 after being folded to be swung on the post in the direction indicated by the arrows in Figure 1 to assume a compact position within the case. A strap 29 on the post is provided to secure the means 14 folded and within the case.

The cymbals are indicated by the character 30 being of a conventional construction and operated through the sliding movement of a rod 31. Also the cymbals are removably mounted on a foldable stand 32 with the rod extending downwardly therethrough. The stand 32 includes a tubular member 33 for the accommodation of the rod 31 and on which the cymbals 30 are removably mounted, and the rod has a link 34 pivoted thereto and to the other treadle heretofore mentioned and indicated by the character 35. The stand 32 further includes foldable legs 36. The lower end of the tubular member 33 is hingedly connected, as at 37, to the supporting means 14 and on which the treadle 35 is pivotally mounted. The cymbals 30 may be removed from the stand 32 and mounted on a rack 38 provided therefor within the case.

The tubular member 33 of the stand includes sections held in operative position by a sleeve 39 having a sliding fit with one section and threaded onto the other section. By detaching the sleeve 39 from the last mentioned section, the tubular member of the stand may be folded. The operating rod 31 of the cymbals located within the

tubular member is provided with a hinged joint 40 to permit folding thereof along with the folding of the sections of the stand, as shown in Figure 10.

The supporting means 14 includes hingedly connected sections 41 and 42, the section 41 resting flatly upon the floor when the cymbals are in playing position, as shown in Figure 4, and is connected to the lower end of the tubular member of the stand 32. The treadle 35 is pivotally mounted on the section 41. The section 42 is of telescopic construction so that it can be adjusted as to length and is pivotally connected to the collar 28. A fastener 43 is provided for securing the telescopic parts in adjusted position. Thus it will be seen that after the stand 32 has been folded it can, with the sections 41 and 42, be arranged in the case and secured in the folded position by the strap 29.

20 The inner face of the door 7 is equipped with a plurality of racks in which various types of tools may be arranged as well as the drum sticks. The tools are utilized in the assembly and care of the device and for making repairs and adjustments to the musical instruments.

25 Thus it will be seen that after the drum has been removed from its support and both of the supporting means 13 and 14 arranged in the case as well as the cymbals and seat, the drummer will 30 only have the case to carry along with the drum when traveling from place to place. Further, it will be seen that the entire device can be conveniently arranged for supporting the drum and cymbals in playing position and that they will 35 be conveniently located whereby the drummer sitting on the seat can easily actuate them through the operation of the foot treadles by his feet.

While I have shown and described the preferred 40 embodiment of my invention, it will be understood that minor changes in construction, combination and arrangement of parts may be made without departing from the spirit and scope of the invention as claimed.

45 Having thus described my invention, what I claim is:

1. In a device of the character described, a portable case, a post mounted in said case with one end exposed exteriorly thereof, a seat detachably connected to said end of the post, means in the case for the accommodation of the seat when removed from the post, and foldable means mounted on said post and extendable from said case for the support of musical instruments.

50 2. In a device of the character described, a portable case, a post mounted in said case with one end exposed exteriorly thereof, a seat detachably connected to said end of the post, means in the case for the accommodation of the seat when removed from the post, a foldable drum supporting means carried by the post and movable into and out of the case, and foldable cymbal supporting means journaled on the post and movable into and out of the case, a foot operated

55 means for a drum carried by the drum supporting means and foldable therewith, and foot operated means for the cymbals carried by the cymbal supporting means and foldable therewith.

3. In a device of the character described, a carrying case including a hinged door, a post mounted in said case with one end protruding exteriorly thereof and having a seat detachably connected thereto, a drum supporting means mounted on said post and including hingedly connected sections, one of which is adjustable as to length and

extendable to be arranged outwardly of the case for the support of a drum and foldable to be arranged within the case, means for removably mounting a drum on said drum supporting means, a treadle operated drum beating element carried by said means and foldable relative thereto.

4. In a device of the character described, a carrying case including a hinged door, a post mounted in said case with one end protruding exteriorly thereof and having a seat detachably connected thereto, a drum supporting means mounted on said post and including hingedly connected sections one of which is adjustable as to length and extendable to be arranged outwardly of the case

for the support of a drum and foldable to be arranged within the case, means for removably mounting a drum on said drum supporting means, a treadle operated drum beating element carried by said means and foldable relative thereto, a cymbal supporting means journaled on said post and including hingedly connected sections foldable to be arranged within the case and extendable to protrude from the case, and a foot operated cymbal actuating mechanism carried by the cymbal supporting means and foldable relative thereto.

BOB C. RENTIE.
